UNITED STATES PATENT OFFICE

92,520

DESIGN FOR A VERTICAL BUMPER

Alphonso S. Campbell, Winchester, Mass.

Application September 18, 1933, Serial No. 49,279

Term of patent 7 years

To all whom it may concern:

Be it known that I, ALPHONSO S. CAMPBELL, a citizen of the United States, residing at Winchester, county of Middlesex, and State of Massachusetts, have invented a new, original, and ornamental Design for a Vertical Bumper, of which the following is a specification, reference being had to the accompanying drawing, forming part thereof.

In the drawing:—

Fig. 1 is a front elevation of the vertical bumper designed for attachment on the usual horizontal bumper of an automobile and as it would be seen from the end of the automobile; and

Fig. 2 is a side elevation thereof.

I claim:—

The ornamental design for a vertical bumper, substantially as shown and described.

ALPHONSO S. CAMPBELL.
